(57) **CLAIM**

The ornamental design for an absorbent pad with fasteners, as shown and described.

DESCRIPTION

FIG. 1 is a front, bottom, left side perspective view of an absorbent pad with fasteners according to an embodiment of the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlargement of the portion indicated in FIG. 1;

FIG. 9 is an enlargement of the portion indicated in FIG. 2;

FIG. 10 is an enlargement of the portion indicated in FIG. 3;

FIG. 11 is an enlargement of the portion indicated in FIG. 4;

FIG. 12 is an enlargement of the portion indicated in FIG. 5;

FIG. 13 is an enlargement of the portion indicated in FIG. 6;

FIG. 14 is an enlargement of the portion indicated in FIG. 7;

FIG. 15 is a front, bottom, left side perspective view of an absorbent pad with fasteners according to another embodiment of the new design;

FIG. 16 is a front side elevation view thereof;

FIG. 17 is a rear side elevation view thereof;

FIG. 18 is a left side elevation view thereof;

FIG. 19 is a right side elevation view thereof;

FIG. 20 is a top plan view thereof;

FIG. 21 is a bottom plan view thereof;

FIG. 22 is an enlargement of the portion indicated in FIG. 15;

FIG. 23 is an enlargement of the portion indicated in FIG. 16;

FIG. 24 is an enlargement of the portion indicated in FIG. 17;

FIG. 25 is an enlargement of the portion indicated in FIG. 18;

FIG. 26 is an enlargement of the portion indicated in FIG. 19;

(Continued)

FIG. 27 is an enlargement of the portion indicated in FIG. 20; and,

FIG. 28 is an enlargement of the portion indicated in FIG. 21.

The broken lines shown in the drawings illustrate portions of the absorbent pad with fasteners that form no part of the claimed design.
